DISK-TYPE GAS HOLDER

Bruno Schäfer, Philipsburg, Germany

Application December 22, 1934, Serial No. 758,854
In Germany December 20, 1933

2 Claims. (Cl. 48—174)

The present invention relates to gasholders or gasometers, more particularly to so-called disk-gasometers.

The known disk-gasometers generally consist of a cylindrically formed sheet-iron shell of circular or polygonal cross section in which a closing plate, disk, piston or the like, supported by the gas within the gasometer is movably arranged and the edge of which is made gas-tight 10 grease supplied under pressure or an oil seal extending all around the circumference.

The air space above the closing plate, the extent of which varies with the volume of gas in the gasometer, is covered with a roof. By means 15 of a seal, slide, flap or the like, upon the center of the roof, movement of the closing plate is made possible, as this sealing arrangement with rising and falling disk allows blowing off of displaced air and prevents the formation of a vacuum 20 in the upper space of the gasholder respectively.

The construction of a gasometer or gasholder is rather dangerous, as in case of unexpected 25 accidents, for instance in case of explosion or fire in the immediate neighborhood of the gasholder, the destruction, warping or bending of the wall of the gasometer or of the closing plate or of both simultaneously may occur which would render the tightening means between the closing 30 plate and the wall of the gasometer or gasholder inoperative.

Depending on the extent of the damage to the 35 gasometer, quantities of gas enter the air space above the closing plate and form an explosive mixture of gas and air which on ignition explodes and not only causes bursting of the gasometer but sometimes may cause destruction over a relatively large area. The danger increases the smaller the quantity of gas in the gas 40 holder and the smaller the opening of the venting arrangement in proportion to the size of the air space filled with the mixture of gas and air.

To obviate this danger, it has already been proposed to cover completely or in zones the roof 45 and even the upper part of the gasometer also with a firm weather-proof fabric, for instance balloon material, celluloid, acetyl cellulose etc., which easily yields to the bursting pressure.

This proposal which was intended to solve the 50 problem of eliminating the disastrous results of ignition of an explosive mixture formed in the air space on top of the closing plate, is, however, not particularly suitable for actually obviating this danger, the more so, as the totally enclosed 55 space on top of the closing plate is still present

and, moreover, burning celluloid pieces thrown out during an explosion may cause dangerous fires in the neighborhood of the gasometers, (benzol tanks and benzol store places).

Now, it has also already been proposed to constantly vent the air space of the gasometer. According to this proposal the wall of the gasometer is provided with openings which may be closed and controlled in such a manner, that they open above the closing plate but close beneath the 10 same and when so closed, are gas tight. To carry out this proposal is correct in itself, would, however, considerably complicate the operation of the gasometer and require a constant control of the openings and control means. 15

According to a further proposal the gasholder or gasometer is to be constructed without a roof. In such a case, however, the closing plate and particularly the tightening or sealing means would be more or less exposed to all kinds of atmospheric conditions unfavorable to its operation, so that water separators for the sealing liquid as well as for the mechanical packing elements would be necessary, thus increasing the 20 costs and making the apparatus still more complicated. 25

The present invention avoids all the disadvantages mentioned above, and according to this invention it is possible to construct disk-gasometers which even though provided with a roof excludes the possibility of the formation and collection of an explosive mixture of gas and air in the space above the closing plate of the gasometer. The invention consists in providing, as a top cover for the disk-gasometer, a roof which 30 extends far out beyond the circumference of the gasometer, and which roof is in the form of a funnel, the downwardly extending portion of which serves as a discharge tube. The roof is mounted upon the gasometer in such a manner, that a space is provided open in all directions and the cylindrical wall shaped opening (i. e., the lateral surface of that part of the gasholder which is in open communication with the atmosphere) is at least equal to approximately 35 the inner cross section of the gasometer. Other features of the invention will be explained in the following description. 40

In the accompanying drawings forming part of 50 the specification some embodiments of the invention are shown by way of example.

In these drawings:

Figure 1 is a view partly in section of a disk-gasometer according to the invention, 55

Fig. 2 shows a view similar to that of Fig. 1 illustrating a modification, and

Fig. 3 is a broken away view of still another modified construction of gasometer according to 5 the invention.

According to the invention the struts 1 (double I-beams or the like) which strengthen the structure are, as shown in Figures 1-3, extended above the upper edge 2 of the wall 3 of the gasometer 10 to such a height that between the edge 2 and the ring 5, supporting the roof 4, a cylindrical opening 6 remains which is so dimensioned, that quantities of gas which have entered the air space on top of the closing plate 7 are at once 15 blown away and may freely flow away and, in case of ignition, may freely burn without an explosion occurring.

For gasometers of relatively small height having a large cross section, this requirement is fulfilled, if the section of free passage of the cylindrical opening is at least as great as the horizontal cross section of the gasometer. (In this case the distance between the edge 2 of the gasometer and the supporting ring 5 must at least be equal 25 to $\frac{1}{2} r$). For higher constructions wherein the ratio of diameter to height is smaller, it is preferable to increase the distance between the parts 2 and 5 to as much as $\frac{2}{3} r$, or even r (where r is the radius of the gasometer).

30 In connection herewith, for the purpose of reducing the resistance against pressure waves coming from below, the roof 4 is formed in accordance with the invention as a smooth or folded funnel provided with a rim 8 and extending far over the 35 gasometer cross section. This funnel is mounted upon the gasometer leaving a space 6, open in all horizontal directions, and having at least the dimensions stated above and thus protects the gasometer against rain and other weather conditions. Its downwardly extending portion 9 40 serves as a tube for discharging rain- or snow-water.

The discharge tube 9 runs vertically downward through the gasometer to a point below the bottom of the latter, where, in the construction shown in Figure 1, it is supported and rigidly fixed in a pot-like foundation 10. The water collected in the funnel is passed by the tube 9 to a pit or convenient place of utilization. The tube 9 may, 45 however, be laterally bent and then, in a manner shown in Figure 3, be passed downwardly at the outside of the wall of the gasometer. In the first of these two cases the invention is applied to gasometers with central disk guiding, the central 50 guiding serving as tube 9 for discharging the water as shown in Figures 1 and 2, whereas in the second case the invention is applied to gasometers the edge of the disk 7 of which is guided by rollers or corresponding guiding means.

60 According to the modifications shown in Figures 1 and 2, the slide piece 11, serving to guide the closing plate 7 and arranged with some play concentrically to the central discharge tube 9, consists of two portions the flanges 12 and 13 of 65 which are bolted together and hold between them the closing plate 7 in a gas-tight manner. The upper portion of the slide piece 11 is enlarged to form an oil cup 14, whereas the lower portion in the lowermost position of the closing plate or disk 7 is received by, and snugly fits into, a pot-like shaft 10 arranged below the bottom 16 of the gasometer. This pot-like shaft is designated by 70 10 in Figure 1 and by 15 in Figure 2.

75 This arrangement renders it certain that, with the closing plate 7 resting upon the bottom 16,

the gasometer is completely emptied, thus absolutely preventing explosions which, for instance, have happened with empty wet water-cup gasometers owing to the fact that traces of gas still remained in the gasometer after long periods of 5 idleness at the end of which repairs (welding, etc.) were undertaken.

The roof funnel 4 and the discharge tube 9 are rigidly connected together by flanges 17, 18 which in turn support the upper oil cup 19 (Figures 1 and 2). The lower flange 18 also fixes the highest possible position of the closing plate 7, i. e. the maximum capacity of the gasometer, the upper edge of the cup-like enlargement of the slide piece 11 in its uppermost end position 15 coming into contact with the flange 18.

Oil for sealing purposes flows from the upper oil cup 19 along the discharge tube 9 into the cup-like enlargement 14 of the slide piece 11 and is simultaneously passed from there to the edge 20 seal 7' of the closing plate 7. The oil flowing downwardly between the slide piece 11 and the tube 9 serves the double purpose of sealing and lubricating. The oil flowing downwardly from beneath the sealing means along the inner wall 25 of the gasometer and along the discharge tube 9 is collected and after filtration pumped again to the upper oil cup 19.

Access to the roof 4, for instance from the upper oil cup 19, may be obtained by a closeable 30 opening 20. The roof 4 may, as shown in Figures 1-3, be provided with a perforated plate or sieve 21 to protect the discharge tube 9 from clogging.

Finally, doors 22 may be provided at the outer 35 wall of the gasholder or gasometer which are arranged at suitable distances from each other and particularly at the level of the gangways. The doors 22 are provided with flanges and sealed by rubber strip packings between the flanges and the outer surface of the wall of the gasometer. The inner surfaces of the doors 22 and the gasometer wall are flush and the doors 22 are, in a known manner (Morton-closure), pressed against the gasometer wall (Figures 1 to 3). In this manner direct access may be had to the closing plate 7 in its highest and lowermost position as well as in any intermediate position. In case of danger or repairs made on the plate 7, the doors 22 above the plate 7 may be opened to increase 50 the venting by draft acting from below.

By the means described above the following advantages are obtained over the known constructions and the proposals made already.

Under normal operating conditions the gas- 55 holder or gasometer is burst-proof, as the formation and collection of an explosive mixture of gas and air above the closing plate or disc 7 is avoided, and under abnormal conditions (air attacks, remote cannonade or bombardment) the 60 gasometer is also burst-proof, as the gas at any portion of the gasholder may burn without causing an explosion. Furthermore, in spite of its large open construction, the gasometer or gas- 65 holder is provided with an effective protecting roof extending far over the cross section of the gasholder, so that even under the most unfavorable wind and weather conditions the closing plate is free from atmospheric deposits and therefore water separators, snow removers, etc., are 70 not required.

The uniformity of the gas pressure is therefore assured in the same manner as with the closed disk-gasometers as constructed hitherto.

By using the central guide 9 as a tube for dis- 75

charging atmospheric deposits from the funnel-shaped roof and due to the strong construction element consisting of the funnel-shaped roof and its discharge tube extending over the entire gasometer, the stability of the gasholder according to the invention, particularly against horizontal wind pressures, is increased to such a degree that the stability is not any longer dependent on the stiffening action of the interior gas pressure.

10 The order of dimensions of the structure (measured in cubic meters of practically useful space) is, therefore, considerably increased.

The erection of a gasholder according to the invention does not offer more difficulties than that of any other waterless gasometer.

Finally, any disk- or piston-gasometer of known construction may, without difficulty, in short time be changed to a burst-proof gasholder according to the invention.

20 With disk-gasometers of the construction shown in Figure 1 the bottom 16 of which directly rests upon the foundation 23, the lower end of the discharge tube 9 extends below the bottom and is arranged and rigidly fixed in a pot- or 25 shaft-like foundation member 10. If, however, it is desired to mount the disc-gasometer on elevated supports, obtaining a space below the gasometer to inspect same from below or for using this space beneath the gasometer for other purposes, the lower end of the central discharge tube 9 is preferably extended into a pot-like casing 15, fixed to the bottom 16 of the gasholder in the 30 space between the latter and the ground, so that free access may be obtained to this casing 15 from all sides. This casing 15, fixed in the manner of a hanger-frame to the under face of the edge of a circular opening 24 in the gasometer bottom 16 so as to obtain a gas-tight connection, corresponds in its shape to that of the slide piece 35 11 of the up- and downwardly moving disk 7 which slide piece serves as circular packing. The casing 15 is provided with lateral sockets 25, 26 to which the gas supplying and discharging tubes are connected. The lower portion of the central 40 discharge tube 9 is, as may be seen from the drawings, fixed to the bottom of the pot-like casing 15 and, by means of a gas-tight connection, is in communication with means for disposing of material passing through said tube 9. The 45 circular opening in the bottom of the casing 15 allows the discharge tube 9 some play which is necessary to be able to effect an exact vertical and axial adjustment of the tube 9 at any time.

50 The bottom of the gasholder or gasometer is, as shown in Figure 2, stiffened by an arch-shaped lattice work construction 28 and the pot-like casing 15 then freely depends from the bottom 16 of the gasholder and from this arch-shaped lattice work construction 28. As the funnel-shaped roof 4 is at 5 supported by angle irons or the like from the whole supporting structure and the discharge tube 9 in turn is rigidly connected to the funnel-shaped roof 4, the bottom of the pot-like casing 15 carrying the lower end of the central discharge tube 9 is only moderately loaded, so that the support of the bottom 16 of the gasholder by a simple lattice work structure or the like is quite sufficient to withstand or resist all forces acting upon the bottom of the gasometer. The 55 pot-like casing 15, centrally arranged as described above, further simplifies the gasometer construction, in that it may be used as a vessel receiving the oil flowing downwardly at the walls of the gasholder. For this the effect aimed at, the bottom 16 of the gasholder is, as shown in

Figure 2, provided with radially extending grooves or folds the depths of which increases towards the center. On account of the inclination of the grooves or the like, a natural flow of the oil to the pot 15 is obtained.

5 Safety requires that, if the gasholder has been emptied, for instance for the purpose of repairing a gasholder out of use, no gas be present under the closing plate or disk 7, that is to say, that the lower portion of the slide piece 11 completely 10 fills the pot 15 and the disk 7 rests flat upon the bottom 16 of the gasometer. In a gasometer without edge-cup (Figure 2), instead of a piston-like closing plate 7 according to Figure 1 the circumference of which forms a cylindrical ring, a 15 horizontal plane disk, as shown in Figure 2, must be used, the edge seal 7' of which is arranged not below the plane of the disc, but above same or at least in the same height as the latter.

20 Such an arrangement, however could easily have the disadvantage, that most of the oil flowing from the edge seal into the space below the disk 7 would not run downwardly along the wall of the gasholder, but in an inappropriate manner 25 would flow away from the latter along the under surface of the disk 7 from which it would drop off finally and reach the bottom of the gasholder. The result of this would be an imperfect and unequal moistening of the wall of the gasholder below the disk or closing plate 7 which would reduce the efficiency of the edge seal 7' on the downward movement of the disk 7 and thereby prejudice the safe operation of the gasometer.

30 To obviate this disadvantage, the peripheral 35 edge 7" of the disk 7 above which the edge seal 7' is arranged, is, according to the invention, arched in the manner of a drain-pipe of a roof, the opening of this drain-pipe being directed downwardly. By this means it is obtained, that 40 the sealing liquid is completely supplied to the wall of the gasometer below the disk 7.

What I claim is:

1. In a disk gasometer, a reservoir consisting of a cylindrical wall closed at its lower edge and 45 open at its upper edge, struts reinforcing said cylindrical wall extending vertically above the upper edge of said reservoir, a funnel-shaped roof of greater diameter than that of said reservoir fixed to the free ends of said struts, a tube 50 fixed to the lower central part of said funnel-shaped roof, a pot-like member fixed to the bottom of said reservoir and forming a support for the lower end of said tube, a two-part slide surrounding said tube, and a closing plate for said 55 reservoir connected to said slide in gas-tight relation, said struts extending a distance above the upper edge of said reservoir sufficient to obtain, between said roof and the upper edge of said reservoir, a space the cylindrical opening of which 60 is at least approximately equal to the internal cross-section of the gasometer.

2. In a disk gasometer, a reservoir consisting of a cylindrical wall closed at its lower edge and 65 open at its upper edge, struts reinforcing said cylindrical wall extending vertically above the upper edge of said reservoir, a funnel shaped roof of greater diameter than that of said reservoir fixed to the free ends of said struts, a tube fixed to the lower central part of said funnel-shaped 70 roof, a pot-like member fixed to the bottom of said reservoir and forming a support for the lower end of said tube, a two-part slide surrounding said tube and a closing plate for said 75 reservoir connected to said slide in gas-tight

relation, the lower end of said slide being formed and proportioned to snugly fit said member to allow the closing plate into close contact with the bottom of the reservoir and the upper end of said slide constituting an oil reservoir containing oil for supplying the edge seal of the closure plate, and said struts extending a distance above

the upper edge of said reservoir sufficient to obtain, between said roof and the upper edge of said reservoir, a space the cylindrical opening of which is at least approximately equal to the internal cross-section of the gasometer.

5

BRUNO SCHÄFER.
